(57) CLAIM

The ornamental design for an electronic guitar simulator, as shown and described.

DESCRIPTION

FIG. 1 is a top, front, left side perspective view of an electronic guitar simulator of the present invention;

FIG. 2 is an exploded bottom, rear, right side perspective view of the electronic guitar simulator of FIG. 1;

FIG. 3 is a top plan view of the electronic guitar simulator of FIG. 1;

FIG. 4 is a left side elevational view of the electronic guitar simulator of FIG. 1;

FIG. 5 is a front elevational view of the electronic guitar simulator of FIG. 1, the rear elevational view being a mirror image thereof; and,

FIG. 6 is a bottom plan view of the electronic guitar simulator of FIG. 1.
